UNITED STATES PATENT OFFICE.

JEHIEL P. SMITH, OF FROBISHER, SASKATCHEWAN, CANADA, ASSIGNOR OF ONE-TWENTIETH TO HENRY STEWART MARTIN, OF ALAMEDA, CANADA, AND THREE-ELEVENTHS TO CHARLES SETH CHAPPELL, THREE-FOURTEENTHS TO ERIC O. CHAPPELL, AND ONE-EIGHTH TO MILES McCAY, OF OXBOW, CANADA.

SHOCK-LIFTER.

No. 919,650.

Specification of Letters Patent.

Patented April 27, 1909.

Application filed July 11, 1906. Serial No. 325,685.

To all whom it may concern:

Be it known that I, JEHIEL P. SMITH, of the village of Frobisher, in the Province of Saskatchewan, Canada, farmer, have invented certain new and useful Improvements in Shock-Lifters, of which the following is the specification.

My invention relates to agricultural implements, of the class more especially adapted for the gathering, lifting and carrying the shock or sheaves from the field to the thresher, and the object of the invention is to provide a strong, convenient, and serviceable shock lifter, which will do away with a great deal of the excessive draft and also give a speedier and less expensive means for handling the shocks than has heretofore been employed.

It consists essentially of an inclined platform, combined carriage and drive wheels to the rear, swiveled wheels toward the front, pivoted adjustable fingers extending forwardly and downwardly from the frame, a rotatable shaft extending across the front, a frame work supported from and extending across the front, and around the platform, gear wheels rigid with the rotatable shaft, friction clutches in engagement with the drive wheels, sprocket chains connecting the friction gears with the shaft gears and means for operating the friction gears and the fingers, all arranged and constructed as herein-after more especially described.

Figure 1, is a perspective view of my complete invention parts being broken away for the sake of clearness. Fig. 2, is a rear elevation of the shock lifter parts being omitted for the sake of clearness. Fig. 3 is a perspective view showing the parts enlarged as compared with Figs. 1 and 2, while Fig. 4 is an elevation partly in section of Fig. 3.

In the drawings like letters of reference indicate corresponding parts in each figure.

A is the inclined platform, which is suitably supported on longitudinal and transverse cross beams $A^1 A^2$, and may have its upper face completely covered or lined with galvanized or sheet iron, in order to make a smoother and stronger surface.

B is a shaft extending completely across below the rear of the platform, and is rotatably supported from bearings in the beams.

B^1 are carriage wheels at either end of the shaft B and rigid therewith.

C is a rod extending forwardly across the platform and secured at its ends to the platform. It is to be understood that such rod is practically in a line with the platform and extends theret beyond.

C^1 is a shaft bearing in the side arms C^2 of the rod C¹, and it extends across the platform slightly in front of the forward cross beams.

D are fingers pivotally supported on the shaft C¹, passing outwardly over the rod C, and are equal in length and parallel the one with the other. D¹ is a second cross rod placed between the rod C and the shaft C¹ and passes directly below each of the fingers. The end fingers D² are secured at their inner ends to the shaft C¹ and have the rod D¹ rigidly fastened thereto, and the successive fingers normally rest upon the rod C.

The front of the platform is cut away leaving alternate openings E and projecting portions E¹. Into and through the openings the fingers D extend. In order that the implement may better withstand the requirements of the work for which it is adapted, the projecting portions E¹ may be formed from a heavier metallic strip than the cover of the platform proper, and when such strip is put in place the portions E¹ will be turned at their outer end over the rod C, the back part of the strip being secured on the outer face of the platform.

F is a metallic strip passing across the platform and toward the front, and has its ends F¹ turned upwardly and outwardly to form bearings for a swivel wheel G. The position of the strip and the dimensions of the swivel wheels are such that the fingers D normally rest on the ground or slightly above. If it be desired the swivel wheels may be done away with and shoes placed beneath the platform, but I prefer the wheel.

H is a roller bearing in the shaft H¹, which is supported and slideable within extending arms H² extending from the upper and lower faces of the platform.

I is an operating handle loosely pivoted from the side beams and fulcrumed by a pin I² from the shaft H¹. Means are provided for fastening the free end of the handle in

any required position. The object of such a roller will be explained hereafter.

5 J^1 are posts secured through the platform and extending vertically upward around its outer edge, and the forward set J^1 are somewhat higher than the rest in order to allow the free passage of a shock therebetween.

J^2 J^3 are a series of reinforcing trestle rods, and J^3 is a strengthening cable extending 10 across between the front posts. The rods J^4 pass forwardly beyond the front posts J^1 and form at their ends a bearing for a shaft K .

K^1 is a gear wheel rigidly secured to the crank shaft K , and the said shaft is so formed 15 that the body K^2 lies to one side of the pivots in the rod J^4 .

L is a friction drive on the main shaft B , and L^1 is a friction clutch normally held in engagement with the drive by a spring L^2 20 involving the shaft.

M is a gear wheel intricate with the friction clutch and M^1 is a sprocket or gear chain communicating the motion of the clutch gear to the eccentric shaft gear. If necessary the 25 friction clutch, the friction drive, and the sprocket wheel and chain may be duplicated on the opposing side of the platform.

N is the ordinary form of spring seat supported from the central beams which extend 30 to the rear of the platform.

N^1 are uprights secured to the beams having a cross bar N^2 dependent therefrom.

O is a wheel centrally supported from the bar N^2 , and having a groove extending 35 around its periphery, and ratchet teeth O^1 disposed circumferentially therearound to the inner side of the groove.

P is an operating handle secured rigidly to the wheel and it is to be understood that 40 such handle is easily accessible from the seat of the operator.

P^1 is a spring or gravity pawl suitably supported in engagement with the ratchet teeth.

P^2 is a foot lever pivoted from one of the 45 uprights N^1 , and directly connected with the pawl by a rope or wire P^3 . Secured diametrically opposing within the channel on the wheel are a set of cables or ropes Q , which pass across and forwardly along the frame 50 being guided by loops Q^1 secured to the frame; the other end of the rope is fastened to the outer extremity of the end fingers D^2 .

R is a foot lever within convenient range of the seat and is connected by a rope or wire 55 R^1 directly to the eye extending from the friction clutch.

It is to be noted that the fingers D D^2 have their forward or free ends formed preferably in the shape of a shoe or simply rounded.

60 The actual operation and use of the implement is as follows: The shocks when gathered have to be picked up and carried from various parts of the field, and are generally carried direct to the thresher by several 65 teams of horses with the ordinary wagons.

To decrease the number of teams and also to save a great deal of unnecessary manual labor my implement is provided. The whiffle trees are attached by ropes or chains through the eye R^X . In pulling over the 70 field the pitch of the machine is such that the fingers just clear the ground in front and the motion of the carriage wheels revolve the shaft K . The driver or operator from the seat N , has full control of both the 75 height of the fingers and also the rotation of the shaft K . When approaching a shock it passes between the horses to the front of the machine and is picked up by the fingers. The operator governs if necessary the rotation of the shaft K so that after a shock has 80 reached the fingers the revolving shaft catches the shock somewhere below its center and pushes it rearwardly up on to the platform. Successive shocks are loaded by 85 a similar operation, the first being forced backwardly by the ones following it. It is to be noted that the driver by means of the foot lever R and the connecting wire R^1 can throw the friction clutch out of engagement 90 with the driving clutch, and in so doing stop the motion of the shaft K , and, that, immediately upon releasing his foot from the lever the friction clutch engages the driver. Such is necessary in order that when 95 approaching the shock the shaft K may be gaged in its rotation so that it will catch the shock below its center. It is further to be noticed that owing to the particular suspension of the fingers D D^2 that any of the individual fingers D may raise themselves to clear a knoll or such small obstruction, and in cases where it is necessary to raise all the fingers such may be done by the movement 100 of the handle P , which raises the end fingers D^2 and necessarily those D .

I wish it to be understood that the implement may be made as shown in the drawings, that is, with the long side to the front, or reversed and with the narrow side to the 110 front. My reasons for making the machine in the form shown is that it is preferable in smooth or level country, but the other form would be more serviceable in less level country, and where roads or highways are more 115 prevalent.

In the wide form the roller H is adjustable, in order that when the machine is taken on the highway the carriage wheels B^1 may be thrown out of commission, and the 120 complete frame drawn from the side on the swivel wheels G , and the rollers. It may also be found necessary to provide an attachment at the front of the machine under guidance of the operator for further raising 125 it from the ground if the adjustment provided by the lever does not suffice. Such may be attached to the swivel wheel and of any convenient form.

Although I have shown one method of 130

driving the crank shaft, any other suitable means might be employed, such being by means of a shaft eccentrically pivoted to the drive shaft B at its rear end, and connected 5 at its forward end to a crank integral with the crank shaft.

What I claim as my invention is:

1. In a device of the class described, the combination with the main carriage wheels of 10 a platform, a set of swivel wheels toward the front and supporting the platform normally inclined, adjustable fingers extending forwardly and downwardly from the platform, a railing to the platform, a crank shaft carried by the railing and above the fingers, and means for revolving and controlling the revolution of the shaft, as and for the purpose specified.

2. In a device of the class described, the combination with the rear carriage wheels and the platform of the main shaft rotatably supported from the platform and rigid with the carriage wheels, adjustable fingers extending forwardly and downwardly from 25 the platform, a set of swivel wheels supporting the platform forwardly, a railing extending around the upper face of the platform, a crank shaft carried by the railing and located above the fingers, a gear wheel on the shaft, 30 a friction drive on the main shaft, a friction clutch normally engaging with the friction drive, a sprocket wheel integral with the friction clutch, an endless gear chain connecting the gear wheels, and means for disengaging the clutch with the friction drive, as and for the purpose specified.

3. In a device of the class described, the combination with the platform and its supporting wheels of a series of yielding fingers, 40 end fingers extending forwardly from the platform, means for controlling the vertical

position of the end fingers, a reinforcing railing extending upwardly from the platform, a rotatable crank shaft above the fingers, and means for controlling the rotation 45 of such shaft, as and for the purpose specified.

4. In a device of the class described, the combination with the carriage wheels and a metallic sheeted platform carried thereby of an outer rod extending forwardly across, 50 and beyond the platform, said platform having alternate open and projecting portions therein adjacent said rod and said projecting portions passing over and around said rod, said rod having side arms, an inner 55 cross rod bearing within the side arms of the aforesaid rod, and below the platform, a series of fingers pivoted to the inner cross rod and extending forwardly through and beyond the openings and over the outer rod, 60 a rod centrally disposed between the aforesaid rods and secured at its extremities to the end fingers, and means for lifting the end fingers, as and for the purpose specified.

5. In a device of the class described, the 65 combination with a platform and the forwardly extending end fingers, of uprights supported by the rear of the platform and centrally disposed, a cross bar secured to the uprights, a ratchet wheel rotatably supported from the cross bar, a wheel rigid with the ratchet wheel, an operating handle secured to the wheel, a ratchet engaging the ratchet wheel, a foot lever controlling the ratchet, and a set of operating ropes connecting the fingers with the grooved wheel, 70 as and for the purpose specified.
